[57] CLAIM

The ornamental design for a computer control device, as shown.

DESCRIPTION

FIG. 1 is a front view of the computer control device showing our new design;

FIG. 2 is a left side elevational view thereof;

FIG. 3 is a perspective view thereof;

FIG. 4 is a back elevational view thereof;

FIG. 5 is a top elevational view thereof;

FIG. 6 is a right side elevational view thereof;

FIG. 7 is a bottom elevational view thereof;

FIG. 8 is a front elevational of an alternative embodiment thereof;

FIG. 9 is a left side elevational view of an alternative embodiment thereof;

FIG. 10 is a perspective view of an alternative embodiment thereof;

FIG. 11 is a back elevational view of an alternative embodiment thereof;

FIG. 12 is a top elevational view of an alternative embodiment thereof;

FIG. 13 is a right side elevational view of an alternative embodiment thereof; and,

FIG. 14 is a bottom elevational view of an alternative embodiment.
